CLAIM

The ornamental design for a computing device as shown and described.

DESCRIPTION

FIG. 1 is a front perspective view of a computing device showing our new design;

FIG. 2 is a rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left-side elevation view thereof; and,

FIG. 8 is a right-side elevation view thereof.

The broken lines shown in the figures show unclaimed features of the computing device and form no part of the claimed design.
